US0D1095532S

(12) **United States Design Patent** (10) **Patent No.:** **US D1,095,532 S**
(45) **Date of Patent:** **** Sep. 30, 2025**

(54) **KEYBOARD**

(71) Applicant: **Shenzhen Sqt Electronics Co., Ltd.**,
Shenzhen (CN)

(72) Inventor: **Ming Wu**, Shenzhen (CN)

(73) Assignee: **Shenzhen Sqt Electronics Co., Ltd.**,
shenzhen (CN)

(**) Term: **15 Years**

(21) Appl. No.: **29/912,889**

(22) Filed: **Sep. 25, 2023**

(30) **Foreign Application Priority Data**

Jul. 19, 2023 (CN) 202330453945.9

(51) **LOC (15) Cl.** **14-02**

(52) **U.S. Cl.**
USPC **D14/392**

(58) **Field of Classification Search**
USPC D14/315, 331, 333–335, 345, 390–394,
D14/396–401, 440, 455, 456; D18/12
CPC H01H 13/70; H01H 13/84
See application file for complete search history.

(57) **CLAIM**

The ornamental design for a keyboard, as shown and described.

DESCRIPTION

FIG. 1 is a perspective view of a keyboard showing my new design;
FIG. 2 is another perspective view thereof;
FIG. 3 is a front view thereof;
FIG. 4 is a back view thereof;
FIG. 5 is a left view thereof;
FIG. 6 is a right view thereof;
FIG. 7 is a top view thereof;
FIG. 8 is a bottom view thereof; and,
FIG. 9 is an enlarged view of the encircled area 9 of FIG. 2. The dash-dash broken lines depict portions of the keyboard that form no part of the claimed design. The dot-dash broken lines in FIGS. 2 and 9 denote the boundary of the enlarged detail view and form no part of the claimed design.

1 Claim, 9 Drawing Sheets
